THE NORRIS PETERS CO. PHOTO-LITHO., WASHINGTON, D. C.

UNITED STATES PATENT OFFICE.

HENRY E. BOYD, OF MCKEESPORT, PENNSYLVANIA, ASSIGNOR TO NATIONAL TUBE COMPANY, OF NEW YORK, N. Y., A CORPORATION OF NEW JERSEY.

ROTARY PIPE-CUTTING MACHINE.

SPECIFICATION forming part of Letters Patent No. 694,523, dated March 4, 1902

Application filed February 26, 1901. Serial No. 48,940. (No model.)

To all whom it may concern:

Be it known that I, HENRY E. BOYD, a resident of McKeesport, in the county of Allegheny and State of Pennsylvania, have invented a new and useful Improvement in Rotary Pipe-Cutting Machines; and I do hereby declare the following to be a full, clear, and exact description thereof.

My invention relates to machines for cutting off the ends of large-sized wrought-metal pipes, and has for its object a machine of this character which may be adjusted to cut off the ends of various sizes of pipes and which is simple in construction and powerful and efficient in operation.

In the manufacture of wrought-metal pipes of large size, such as are used for water and gas mains, a plate of suitable width and thickness has its edges scarfed and is then bent into tubular form with the scarfed edges overlapping, after which it is heated until the edges are at a welding heat and then passed over a ball between suitable rolls, whereby the overlapped edges are welded together. This operation leaves the ends of the pipe ragged, and generally the welded seam is not perfect at the extreme ends. These imperfect ends must be removed. Heretofore it has been the custom, especially with very large sized pipes having thick walls, to cut off the ends by mounting the pipe in specially-constructed lathes and then rotating the same and bringing an ordinary cutting-off tool mounted in a slide-rest in contact therewith, which gradually and progressively cuts off the end of the pipe. This, of course, is a slow and expensive procedure, although very effective for the intended purpose. It has been attempted to cut off these crop ends of the pipe by means of metal-shearing machines; but the machines constructed prior to my invention were liable to mutilate the ends of the pipe, reduce the diameter, and form beveled edges thereon.

The object of my invention is to provide a machine for this purpose which is particularly adapted for very large sized pipes, which is adjustable within limits for various-sized pipes, and which will not mutilate the ends of the pipe, but will leave the same perfectly circular and of the same diameter as the body

of the pipe and will form square end edges thereon.

To these ends it comprises a rotating barrel on which the shearing-disks are mounted eccentrically, so that when the barrel is rotated said disks are carried around in a circle corresponding to the circular walls of the pipe to be sheared, and which shearing-disks are mounted so as to be adjustable toward and from the center of the barrel.

The invention also comprises certain mechanism for rotating this barrel which is compact and whereby a strong rotative effect may be produced.

The invention also comprises means for moving one of the shearing-disks toward and from the other disks in order to permit the insertion of the pipe end between the same and be cut off thereby, which means is operative at all positions of the rotating barrel and which moves the disks toward and from each other in a straight line.

The invention further comprises certain details of mechanism, as will hereinafter be more fully described and claimed.

In the accompanying drawings, Figure 1 is a side elevation of the machine. Fig. 2 is a plan view of the same. Fig. 3 is a rear end elevation. Fig. 4 is a front end elevation. Fig. 5 is a longitudinal vertical section showing the manner of mounting the barrel. Fig. 6 is a vertical longitudinal section through the barrel. Fig. 7 is a horizontal longitudinal section of the same. Fig. 8 is a transverse section through the barrel, showing the rear head in elevation. Figs. 9 and 10 are sectional detail elevations of the bearing-frames in the front and rear heads, respectively, with the adjusting screws and nuts in place therein. Fig. 11 is a front elevation of the barrel. Fig. 12 is a plan view of the same. Fig. 13 is a front elevation of the slide or carriage carrying the movable cutter. Fig. 14 is a bottom plan view of the same. Fig. 15 is a front view of the frame in which the movable cutter is mounted, and Fig. 16 is a transverse section through said frame and the bearings and arbor on which the movable cutter is mounted.

1 represents a bed-plate on which all of the operative parts of the machine are mounted.

On the forward end of this bed-plate is provided the clamp 2 for holding the pipe 3, whose end is to be cut off. This clamp is provided with two jaws 4 on one side and a single 5 jaw 5 on the opposite side, these jaws being provided with dovetailed bases 6, moving in undercut ways in the plate 7, which plate in turn is mounted to move transversely in undercut ways 8 in the plate 9, suitably secured 10 to the bed-plate 1.

10 represents screws for moving the jaws 4 and 5 forward and back, and these jaws grasp the pipe in the usual way and hold it firmly in position while the end thereof is being cut 15 off. Inasmuch, however, as this clamp is not new and is not claimed herein, a more detailed description thereof is not deemed necessary. Suffice it to say that the clamp is so positioned with reference to the other parts 20 of the machine that the axis of the pipe whose end is to be cut off will be in line with the axis of the rotating barrel, hereinafter to be described.

Suitably secured to or cast with the bed-plate 1, near its middle portion, are two standards 11, provided with semicircular bearing-surfaces, which serve as bearings for the rotating barrel 12. To the upper portions of the standards 11 semicircular bands or caps 13 are suitably secured, as by means of the bolts 14, which bands fit over the barrel 12, so that the barrel is confined between said bands and the bearing-faces on the standards 11, but being mounted therein so as to be 35 freely rotatable. The barrel 12 is provided at its forward and rear ends with collars 15, which bear against the end faces of the standards 11 and caps 13 and prevent endwise movement of said barrel. The barrel is also 40 provided at its middle portion with the peripheral spur-gear 16, which meshes with a spur-pinion 17 on the shaft 18, on which shaft 18 is also secured the spur-gear 19, which meshes with a spur-pinion 20 on the shaft 21. To this shaft is also secured a spur-gear 22, which meshes with a spur-pinion 23 45 on the main drive-shaft 24, said drive-shaft being provided with the pulleys 25, which are adapted to receive a belt from any suitable 50 source of power and by means of which motion is communicated to the machine. The shafts 18, 21, and 24 are mounted in bearings in the housings or brackets 26, bolted to the sides of the standards 11. By means of the 55 gearing described a positive and strong rotary motion is given to the barrel 12, and this gearing is compact and is mounted directly on the frame of the machine. It will be observed that the speed of rotation is being 60 constantly reduced in that a spur-pinion is always in mesh with a comparatively large spur-gear, the result being that the barrel will rotate at a comparatively slow speed with a corresponding increase of power.

65 On the rear end of the bed-plate 1 are secured suitable frames or brackets 27, which support a hydraulic cylinder 28, the piston-

rod of which carries a cone 29, which bears against the roller 30 on the rear ends of the levers 31 for actuating the movable cutting-disk, as will more fully hereinafter appear. The forward end of the cone 29 is provided with a cylindrical extension 32, which projects into a central opening in the hub 33 on the rear end of the barrel 12, whereby said cone 29 is always centered with reference to the barrel and held firmly in a horizontal position. The water connections to the cylinder 28 is through the pipe 34, which is provided with a suitable valve 35 in position to 80 be operated by the attendant of the machine. The cone 29 is provided with hooks 36, to which are attached one end of the flexible cables 37, which pass over the grooved sheaves 38, suitably journaled on the sides of the frames 27, said cables having secured to their opposite ends the counterbalancing-weights 39, which serve to withdraw the cone 29 after it has been projected by hydraulic pressure in the cylinder 28.

Firmly secured in the barrel, as by means of the tap-bolts 40, are the front head 41 and the rear head 42, each of said heads being provided with suitable openings for receiving the bearings for the rotatable shaft 43, which carries at its forward end the stationary cutting disk or anvil 44, and for the passage of the levers 31, which have mounted between their rear ends the roller 30, heretofore mentioned, and which are forked at their front ends and pivotally connected to the links 45, the opposite end of said links being pivoted to a slide or carriage 46, carrying the movable cutting-disk 47, as will hereinafter more fully appear.

The front head 41 is cut away, as at 48, to permit the passage to the shaft 43 and is provided with the ways or guides 49, in which is mounted the bearing-frame 50, said frame being provided with an opening 51 for receiving the bearings 52 and 53 for the shaft 43. This frame 50 is also provided on each side of the opening 51 with the vertical holes 54, said holes being counterbored at their lower ends, as shown at 55, for receiving the nuts or bushings 56, which nuts or bushings bear with their upper ends against the end walls of the counterbored openings 55 and are internally screw-threaded for receiving the screws 58, by means of which the frame 50 and bearings for the shaft 43 may be adjusted toward and from the center of the head 41. The screws 58 are journaled at their lower ends in bearings 59 in the head 41 and have their upper ends journaled in bearings 60 in 110 said head, said screws being thus prevented from endwise movement. The face-plate 61 is suitably secured to the front face of the head 41. To the lower end of each of the screws 58 is secured a spur-gear 62, said spur-gears meshing with a spur-gear 63 on the upper end of the stub-shaft 64, suitably mounted in the head 41 and provided at its lower end with the worm-wheel 65, which meshes with

a worm 66 on the shaft 67, which is mounted longitudinally in the barrel in suitable bearings 68 in the head and which is provided at its forward end with a squared or keyed portion 5 for receiving the crank 69, by means of which said worm-shaft may be rotated and through the worm-wheel 65 and spur-gears 63 and 62 communicates motion to the screws 58, which screws working in the bushings or nuts 56 in the bearing-frame 50 will elevate or lower the same, as may be desired.

The head 41 is cut away on its two opposite sides, as at 70, providing openings for the passage of the levers 31, and formed in said head 15 in the side walls of the openings 70 are the circular seats 71, which are adapted to receive the bosses or trunnions 72 on the inner sides of the levers 31, thereby providing pivotal bearings for said levers. The levers are 20 provided on their outer faces opposite the bosses or trunnions 72 with the convex portions 73, which bear against the inner face of the barrel 12, thereby preventing displacement of said levers and providing a bearing 25 which is fairly free from friction. The seats 71 are formed mostly in the head 41, but are formed partially by concave depressions 74 in the face-plate 61. The face-plate 61 is provided with a suitable opening 75, which corresponds 30 to the opening 48 in the head 41, and with the side openings 76, through which the levers 31 pass, and also with the peripheral notch 77, which fits over the bearing 68, in which the worm-shaft 67 is mounted.

The rear head 42 is provided with suitable ways or guides 80, in which the bearing-frame 81 is mounted, said bearing-frame being provided with the opening 82 for receiving the bearing 83 for the rear end of the shaft 43, 40 said frame also being provided on each side of the opening 82 with suitable vertical holes 84, which holes are counterbored at their upper ends, as at 85, for receiving the bushings or nuts 86, the lower ends of which bushings 45 or nuts bear against the end walls of the counterbored openings 85 and said nuts being internally screw-threaded for receiving the screws 87. These screws are suitably mounted in the lower bearings 88 and upper bearings 89 50 in the head 42 to prevent endwise displacement thereof and have secured to their lower ends the spur-gears 90, which mesh with the spur-gear 91 on the upper end of the stub-shaft 92, suitably mounted in the head 42, and provided 55 at its lower end with the worm-wheel 93, which meshes with a worm 94 on the worm-shaft 67, above referred to. Inasmuch as the thrust on the stationary shearing-disk 44 during the operation of the machine is downward, there is a tendency for the rear end of the shaft 43 to move upward, and the adjusting means must be so constructed as to prevent this upward movement. Consequently 60 the holes in the bearing-frame 81 are counterbored at their upper ends, as at 85, and the nuts 86 bear against the end walls of said counterbored portions and prevent upward

movement of the bearing-frame. In the case of the front bearing-frame, however, the thrust is always downward, and consequently 70 the holes in said frame are counterbored at their lower ends, as at 55, heretofore described, in which lower portion the nuts 56 bear and prevent downward movement of said bearing-frame. By means of the crank 69, 75 worm-shaft 67, and connecting gearing the adjusting-screws both in the front and rear heads are simultaneously actuated, so as to secure an adjustment of the shaft 43 in a parallel line toward and from the axis of the barrel 12. The rear head 42 is provided with suitable openings 95, through which pass the rear ends of the levers 31.

The forward end of the barrel 12 is provided with the radial projection 96, which is 80 provided with suitable ways or guides 97 for receiving the flanges 98 of the slide or carriage 46, in which is mounted the movable cutter 47, said carriage being prevented from displacement by the plates 99, secured to the 85 front face of the projection 96. The slide or carriage 46 is provided with the side studs or trunnions 100, which receive the outer ends of the links 45, the inner ends of which are pivoted to the forked ends of the levers 31, as 90 heretofore described, so that when said levers are actuated by means of the cone 29 the said slide or carriage 46 is moved toward and from the axis of the barrel 12, thereby carrying the movable cutter 47 toward and from the 95 stationary cutter or anvil 44.

The slide or carriage 46 is provided with ways or guides 101, in which ways or guides is mounted a frame 102, said frame being prevented from dropping out by means of the 105 plates 103, which bear frictionally against said frames and are suitably secured to the slide or carriage 46 to overhang the frame 102. To the upper end of the slide or carriage 46 is secured a plate 104, said plate being pivotally mounted at one end and provided at its opposite end with the open hole 105, thereby providing a hook which takes over the bolt 106, whereby said plate is held in position, but so that it can be readily swung 110 sidewise out of place. Passing through this plate are screws 107, which bear against the upper ends of the frame 102 and determine the position thereof, which adjustment of the frame is necessary in order to adapt the machine to cut pipes of different sizes. The adjustment of the frame 102 by means of the screws 107 is limited, and consequently I intend to use changeable frames 102, provided with various-length upward projections 108 120 for certain limits in the sizes of the pipes, the adjustment for sizes of pipes within such limits, however, to be secured by means of the screws 107.

The frame 102 is cut away, as at 109, thereby 130 providing the two legs 110, between which legs are mounted the bearings 111, which bearings have screw-tapped holes in their upper faces for receiving the screws 112, which

pass through openings in the frame 102, by means of which screws the bearings 111 are held in place. These bearings are provided with the unbroken semicircular outer bearing-faces 114, but are grooved out on their inner faces, thereby forming the chambers 115 for receiving waste or other material to aid in lubricating the arbor of the movable cutter, it being understood, of course, that during the cutting operation the thrust on the movable cutter is outward against the bearing-faces 114. The bolts 112 have each an opening 116 passing therethrough, which opening communicates with an opening 117 in the bearing 111, and which is adapted to receive at its upper end the screw-plug 118 for closing the same. Through these openings oil is introduced into the bearings 111.

The movable cutter 47 is secured to the arbor 120 by means of sleeves 121, said sleeves being provided with flanges 122, which bear against the sides of the cutter 47 and are clamped between the head 123 on one end of the arbor 120 and the flanged nut 124 on the opposite end of said arbor. The arbor 120, sleeves 121, and shearing-disk 47 rotate as a single piece in the bearings 111.

The operation of the machine is as follows: The pipe whose end is to be cut off is clamped in the vise 2 in such position that its axis is coincident with the axis of the barrel 12, and the end of said pipe is introduced between the cutter-disks 44 and 47, the cutter-disk 47 being in its outward position for this purpose. The shaft 43 has been moved to its proper position by means of the worm-shaft 67 and connecting mechanism, so that the cutter-disk 44 will bear during the rotation of the barrel 12 upon the inner surface of the pipe 3, and when a different-sized pipe is to be cut off it will be necessary, through the crank 69, to change the position of the shaft 43. So, too, the position of the movable cutter 47 has been fixed by properly adjusting the screws 107, bearing on the upper ends of the frames 102, and, if necessary, replacing said frame by one having a different-length upper end projections 108. The machine being properly adjusted and the barrel put in rotation and the pipe end being entered between the shearing-disks 44 and 47, water is admitted to the hydraulic cylinder 28, thereby forcing the cone 29 under the roller 30 at the rear end of levers 31, whereby the front end of said levers are depressed, drawing down on the links 45 and through said links moving the slide or carriage 46 and the movable cutter 47 inward against the outer face of the pipe, it being understood, of course, that the barrel 12 is rotated constantly, and by reason of the part 29 being a cone this movement can be imparted to the movable cutter 47 at any position of the rotary movement of the barrel. The cutter 47 is moved inward in a straight line and being pressed against the outer surface of the pipe shears down into the same on a straight line, and

this shearing continues around the pipe as the barrel 12 rotates until the entire circumference of the pipe has been traversed, it requiring slightly more than one rotation of the barrel 12 to completely sever the end of the pipe. Hydraulic pressure is then released in the cylinder 28, when the counterbalancing-weights 39 will move the cone 29 backward, thereby permitting the roller 30 and overweighted rear ends of the levers 31 to move the carriage or slide 46, with the movable cutter, outward to permit the insertion of another pipe end, when the operation is repeated.

The machine shown and described is very powerful, the mechanism is compact and as simple as possible, and the operation thereof highly efficient.

What I claim as my invention, and desire to secure by Letters Patent, is—

1. In a pipe-cutting machine, the combination of a rotatable barrel, a stationary disk mounted thereon, a movable cutting-disk also mounted thereon, means mounted in the barrel for moving the movable disk toward and from the stationary disk in a straight line, and mechanism for actuating said means.

2. In a pipe-cutting machine, the combination of a rotatable barrel, a stationary disk mounted thereon, means for adjusting said stationary disk toward and from the axis of the barrel, a movable cutting-disk mounted on the barrel, means mounted in the barrel for moving the movable disk toward and from the stationary disk, and mechanism for actuating said means.

3. In a pipe-cutting machine, the combination of a rotatable barrel, a stationary disk mounted thereon, means for adjusting said disk toward and from the axis of the barrel, a movable cutting-disk, means mounted in the barrel for moving said disk toward and from the stationary disk, said disk being adjustably connected to said moving means, and mechanism for actuating said moving means.

4. In a pipe-cutting machine, the combination of a rotatable barrel, a stationary disk mounted thereon, a movable cutting-disk, means mounted in the barrel for moving the said disk toward and from the stationary disk, means for adjustably connecting said movable disk to the moving means, and mechanism for actuating said moving means.

5. In a pipe-cutting machine, the combination of a rotatable barrel, a stationary disk mounted thereon, a radial guideway on said barrel, a slide or carriage moving in said guide, a cutting-disk mounted on said slide, means mounted in the barrel for moving the slide, and mechanism for actuating said moving means.

6. In a pipe-cutting machine, the combination of a rotatable barrel, a stationary disk mounted thereon, a radial guide on said barrel, a slide or carriage moving in said guide, a cutting-disk mounted on said slide, levers connected to said slide and mounted in the

- barrel, and mechanism for actuating said levers.
7. In a pipe-cutting machine, the combination of a rotatable barrel, a stationary disk mounted thereon, means for adjusting said disk toward and from the axis of the barrel, a radial guide on said barrel, a slide moving in said guide, said slide carrying a cutting-disk, levers connected to said slide and mounted in the barrel, and mechanism for actuating said levers.
8. In a pipe-cutting machine, the combination of a rotatable barrel, a stationary disk mounted thereon, means for adjusting said disk toward and from the axis of the barrel, a radial guide on said barrel, a slide moving in said guide, a cutting-disk adjustably mounted on said slide, and means mounted in the barrel for moving the slide toward and from the stationary disk.
9. In a pipe-cutting machine, the combination of a rotatable barrel, a rotatable shaft mounted therein, said shaft carrying a stationary disk at its forward end adapted to bear on the inside of the pipe, a movable cutting-disk, and mechanism for moving the same toward and from the stationary disk.
10. In a pipe-cutting machine, the combination of a rotatable barrel, a rotatable shaft mounted therein, said shaft carrying a disk at its forward end, means for adjusting said shaft toward and from the axis of the barrel, a movable cutting-disk also mounted on the barrel, and means mounted in the barrel for moving said disk toward and from the stationary disk.
11. In a pipe-cutting machine, the combination of a rotatable barrel provided with heads having ways therein, bearings adjustably mounted in said ways, a shaft mounted in said bearings and carrying a stationary disk, a movable cutting-disk, and mechanism for moving the same toward and from the stationary disk.
12. In a pipe-cutting machine, the combination of a rotatable barrel provided with heads having radial ways therein, bearings in said ways, mechanism for simultaneously adjusting the bearings in both heads, a shaft mounted in said bearings and carrying a stationary disk, a movable cutting-disk, and mechanism for moving it toward and from the stationary disk.
13. In a pipe-cutting machine, the combination of a rotatable barrel provided with heads having radial ways therein, a shaft mounted in bearings and carrying a stationary disk, screws for moving said bearings toward and from the axis of the disk, a worm-shaft and connecting mechanism to said

screws whereby the bearings are simultaneously adjusted.

14. In a pipe-cutting machine, the combination of a rotatable barrel having heads provided with ways, bearings moving in said ways, a shaft mounted in said bearings and carrying a stationary disk, a nut bearing on the upper face of the rear bearing, a nut bearing on the lower face of the forward bearing, screws working in said nuts, and means for simultaneously operating said screws.

15. In a pipe-cutting machine, the combination of a rotatable barrel having heads therein, a shaft mounted in said heads and carrying a stationary disk, levers fulcrumed in the front head, a movable cutting-disk and connections between the same and the front end of said levers, and means adapted to bear against the rear end of said levers to actuate the same.

16. In a pipe-cutting machine, the combination of a rotatable barrel having heads therein, of a shaft mounted in said heads and carrying a stationary disk, of levers provided with trunnions seated in the front head, a movable cutter and connections between the same and said levers, and means for actuating said levers.

17. In a pipe-cutting machine, the combination of a rotatable barrel, a stationary disk mounted thereon, a movable cutting-disk also mounted thereon, levers mounted in said barrel and connected to said movable disk, and means concentric with the barrel and adapted to bear against the rear end of the levers to actuate the same.

18. In a pipe-cutting machine, the combination of a rotatable barrel, a stationary disk mounted thereon, a movable cutting-disk, levers mounted in said barrel and connected to said movable disk, a cone concentric with the barrel and adapted to bear against the rear end of said levers, and a power-cylinder for actuating said cone.

19. In a pipe-cutting machine, the combination of a rotatable barrel, a stationary disk mounted thereon, a movable cutting-disk, levers mounted in the barrel and connected to said movable disk, a cone concentric with the barrel and adapted to bear against the rear end of said levers, a power-cylinder for actuating said cone, and counterweights for withdrawing said cone.

In testimony whereof I, the said HENRY E. BOYD, have hereunto set my hand.

HENRY E. BOYD.
